DISPENSER CARTON

Reynolds Guyer, Peninsula Road,
White Bear Lake, Minn.

Filed July 17, 1958, Ser. No. 51,822

Term of patent 14 years

(Cl. D52—2)

Figure 1 is a perspective view of a dispenser carton in a closed position and showing my new design; and Figure 2 is a perspective view thereof in an open position.

The design for the dispenser carton disclosed is characterized by the top portion as shown.

I claim:

The ornamental design for a dispenser carton, as shown and described.
